SHEET FEEDING AND ASSOCIATING MECHANISM.

Application filed October 6, 1924. Serial No. 741,803.

This invention relates to certain improvements in sheet feeding and associating mechanisms.

In fast rotary printing machines it is frequently desirable to feed in a previously printed sheet, such as an insert or a cover, and to associate these sheets with the product of the press. These specially or previously printed sheets are fed into the machine by automatic sheet-feeding mechanisms. In fast rotary machines, however, the speed at which the products are delivered from the printing machines is usually much higher than the speed at which the automatic sheet-feeders can be operated to feed in the sheets. To utilize the capacity of a high speed machine, therefore, it has been necessary to provide two or more feeders. These feeders are expensive, thus adding considerably to the cost of a press, complicate the press, and, furthermore, with certain types of presses, it is very inconvenient, if not impossible, to position more than one feeder in the desired relation with the printing machine.

It is the particular object of the present invention to produce a sheet-feeding mechanism whereby with one sheet-feeder the specially printed sheets, as covers or inserts, may be fed to a high speed rotary machine and associated with the products therefrom so that the machine may be run to capacity, either with collected or uncollected associated products.

It is a further object of the invention to produce a feeding mechanism which will be simple, economical to construct, and which may be positioned in any desired relation with the press with which it is to be used.

With these and other objects not specifically referred to in view, the invention consists in certain novel parts, arrangements and combinations which will be fully described in connection with the accompanying drawings and the novel features thereof pointed out in the claims hereunto annexed.

Generally speaking, the objects of the invention are carried into effect by the use of multiple sheets, that is,—a sheet consisting of several similar sheets, as covers or inserts, printed in one, and in the provision of a mechanism for separating this multiple sheet into single sheets and feeding the single sheets into the machine in correct, timed re-

lation with the products with which the sheet is to be associated.

Referring to the drawings—

Figure 1 is a side view of the folder end of the printing machine and so much of the improved sheet-feeding mechanism as is necessary to illustrate one embodiment of the invention;

Figure 2 is a plan view of the construction shown in Fig. 1;

Figure 3 is a diagrammatic end view of one cutting and sheet-controlling mechanism for carrying out the invention;

Figure 4 is a similar view of another arrangement of sheet-cutting and controlling mechanism which may be used;

Figure 5 is a similar view of another arrangement of sheet-cutting and controlling mechanism for effecting the objects of the invention;

Figures 6 to 11 inclusive, are diagrammatic side views showing the sequence of operations when a three-part sheet is cut and the sheets are forwarded at intervals of a sheet length to be associated with a collected product;

Figures 12 to 17 inclusive, are diagrammatic side views showing the sequence of operations when a two-part sheet is cut and forwarded at intervals of a two-sheet length to be associated with a product twice collected;

Figure 18 is a diagrammatic side view of a cutting arrangement which may be employed where the sheet is cut with a shear cut;

Figure 19 is a diagrammatic side view of a cutting arrangement which may be employed when the sheet is cut with a reciprocating cutting knife.

Figure 20 is a diagrammatic side view of a modified form of construction which may be employed in conjunction with a reciprocating knife;

Figure 21 is a view similar to Fig. 1, showing an arrangement which may be used with a collected product or an uncollected product; and,

Figure 22 shows a modification of the construction shown in Fig. 21, where compactness of parts is necessary or desired.

Referring now to these drawings, the sheet-feeding mechanism is arranged at the folder end of a printing machine. the cutting

cylinders of which those marked 1, 2, are illustrated, the various parts of the mechanism being supported in frames 3 of any usual or desirable configuration. From the 5 cutting cylinders the product, which may be an associated product, is led between forwarding rolls 4, 5, to the folding mechanism which may be a rotary folder including a collecting cylinder 7 and co-operating cylinder 8, the folding-off rolls of the folder not being illustrated.

In accordance with the invention a multiple sheet is fed into the mechanism from an automatic sheet-feeder, not illustrated, 15 and this multiple sheet is cut into single sheets and the single sheets forwarded to the folding mechanism in correct timed relation with the products of the press. The number of sheets in the multiple sheet may, 20 of course, be varied and the mechanism whereby the multiple sheets are cut into single sheets and forwarded in proper timed relation may also be varied within considerable limits. The single sheets, however, 25 which make up the multiple sheet will be of a number depending on the particular product being produced by the press. For instance, where the product is once collected, the multiple sheet may include three single 30 sheets and these sheets will be cut and forwarded at intervals of a sheet length. Where a product is, however, twice collected, the multiple sheet can be made up of two sheets which will be cut and forwarded 35 at intervals of a two-sheet length. Where the product is not collected a multiple sheet two sheets long can be employed.

Referring first to Figs. 1, 2, 3, and 6 to 40 11, inclusive, the mechanism illustrated is capacitated to cut a three-part sheet into single sheets and associate these single-cut sheets with a press product which has been once collected, that is, in which two products have been collected together. The multiple 45 sheet in this instance is made up of three single sheets, s^1 , s^2 , s^3 . These sheets may be similar, as covers or inserts, or may be of any desired character, depending upon the products with which they are to be associated. In the particular arrangement shown 50 these sheets follow each other in line and are fed into the machine in the direction of the arrow x (Fig. 1), from an automatic sheet-feeder of any desired or usual type, 55 this not having been illustrated as being unnecessary for an understanding of the invention. The multiple sheet is fed between lower forwarding tapes 9, 10 (Fig. 2), passing 60 over pulleys 12 on a shaft 13 mounted in the side frames 3 of the machine and a pair of upper tapes 14, 15, passing over pulleys 15' on a shaft 16, supported in hangers 17, secured to the side frames 3. The lower tapes pass at their other ends over pulleys 65 18 (Fig. 1) on a shaft 19 secured in the side

frames of the machine. The upper tapes pass over pulleys 20, 21 on a shaft 22, carried in bearings 23 on arms 24 on a rock shaft 25 suitably supported in the side frames of the machine. This shaft has an arm 25' connected by a cam-operated rod 26 to lift the pulleys 20, 21 at suitable times to free the sheet. If desired, the upper tapes may be omitted, the pulleys 20, 21, then operating 70 only as a drop roll to control the sheet. 75

The sheet is forwarded by the tapes against a stop 27 located behind the pulleys 20, 21, by which the sheet is properly aligned. After aligning the stop is dropped in any suitable manner and the sheet is forwarded to the cutting mechanism. These parts referred to are driven through connections hereinafter referred to. 80

The cutting mechanism may be varied within wide limits and depending on the 85 number of single sheets into which the multiple sheet is to be cut. In the construction shown in Figs. 1 to 3 and 6 to 11, the cutting mechanism is in the form of a pair of cylinders 28, 29, the cylinder 28, in the particular construction illustrated, being the cutting cylinder, these cylinders being mounted on shafts 30, 31, suitably journaled in the side frames of the machine before referred to. 90

When a three-part multiple sheet is to be cut into single sheets and these sheets are to be associated with a product once collected, the sheets are forwarded, after being cut, 100 at intervals of the length of one sheet so as to provide for association with the product at the proper time. When this construction is employed, the first sheet is cut and forwarded directly to the folder. The second sheet is controlled, as by detaining a sufficient time for a sheet length to have passed and is then forwarded. The third sheet is directly forwarded, as is the first, separated 105 from it by an interval equal to the length of one sheet. The second sheet is detained by either the cutting cylinder or the cylinder co-operating therewith and the cylinder is, therefore, made of such size that by the time the head end of the detained sheet reaches the sheet path and follows the other sections, it will be separated from the third sheet, which has preceded it, by an interval 110 equal to a sheet length. In the particular construction shown in Fig. 3, the sheet is detained by the cutting cylinder. This cutting cylinder 28 and co-operating abutment cylinder 29 are three times the length of the sheet and the cutting cylinder is provided with a pair of cutting knives 32, 33, these knives being spaced apart 120° . These cutting knives cooperate with the usual cutting woods or rubbers 34, 35, provided on the cylinder 29. The cutting cylinder 28 is also provided with sheet-taking devices, these 115 sheet-taking devices being in the form of 120

125 sheet-taking devices being in the form of 130

pins 36 arranged behind and closely adjacent the cutting knives. These pins are mounted on arms 37 operated in the usual manner to project and withdraw the pins. 5 The cutting cylinder is further provided with three sets of fingers 38, 39, 40, which are placed 120° or one sheet length apart, the function of these fingers being to prevent the first and third separated cover sheets 10 from following around the cylinder and to guide them into the sheet path to the folding mechanism.

With the construction so far described it will be apparent that the sheet is cut into 15 three single sheets and these sheets are forwarded in predetermined timed relation to the folder, being separated by an interval equal to the length of one sheet, that is, equal to the time of once collecting the product on 20 the collecting cylinder. The course of the sheets is diagrammatically shown in Figs. 6 to 11. This run may be briefly described as follows:

Referring to those figures, a multiple sheet 25 made up of the sheets s^1 , s^2 , s^3 , is just being fed to the cutting and detaining cylinders. The sheet is advanced the length of the sheet s^1 . At this time the cutting knife 33 severs the sheet s^1 and the pins 36 impale 30 the leading edge of the succeeding sheet s^2 , as shown in Fig. 7. Fig. 8 illustrates the position of the sheet after the cutting cylinder has made one-third of a revolution. When the parts are in this position, the 35 sheet has been taken around the cylinder the length of the sheet s^2 and the cutting knife 32 has arrived in position to sever the sheet s^2 from the succeeding sheet s^3 . The sheet s^3 is now allowed to pass between the cutting 40 cylinders and is spaced from the sheet s^1 one sheet length, as shown in dotted lines in Fig. 9, the cutting cylinder 28 having made two-thirds of a revolution. The last one-third of a revolution of the cylinder 28 permits the sheet s^3 to advance a sheet length, at which time the pins 33 are withdrawn 45 from the sheet s^2 and the sheet s^2 follows the sheet s^3 , being spaced therefrom a sheet length, as shown in dotted lines in Fig. 11. 50 A succeeding multiple sheet, it will be understood, will be held by stop 27 for the distance of a multiple sheet length, as indicated by dotted lines in Fig. 8, so that in the sequence of operations the single sheets are always 55 spaced apart one sheet length. As the second multiple sheet approaches the cutting cylinder, the parts will again resume the position shown in Fig. 6 and the operation be repeated.

60 It will be understood that the stripper fingers 38, 39, 40, operate at the proper time to strip the sheets s^1 , s^2 , s^3 and prevent them from following around the cylinder so that they continue in a straight path direct to 65 the associating mechanism. From the cut-

ting cylinders, the sheets are forwarded through guides 41 by a pair of forwarding rollers 42, 43, and a second pair of forwarding rollers which may include rolls 44 and the cylinder 8, before referred to. 70

In the construction so far described the sheets are associated with the product which has been once collected, that is, two products are associated on a collecting cylinder.

In Figs. 4 and 12 to 17 there is shown a construction which may be employed when a separate sheet is to be associated with a product twice collected, that is, three products associated on the collecting cylinder. Referring to these figures, the sheet which 80 is fed in by the feeder will be a multiple sheet, such multiple sheet comprising two sheet lengths. Where the product is twice collected, these sheets must be forwarded spaced apart a distance of two single sheets 85 and the multiple sheets will be fed to the cutting cylinders spaced apart two multiple sheet lengths. Referring to Fig. 4, there is shown a cutting cylinder 45 mounted on a shaft 46 and provided with a cutting knife 90 47. Cooperating with this cutting cylinder is a cylinder 48 mounted on a shaft 49 provided with a cutting wood 50. Each of these cylinders is of a circumference equal to twice the length of a single sheet. Where, 95 as in the present instance, the cutting cylinder is the detaining cylinder, it is provided with a set of sheet-taking devices, as pins 51, suitably mounted on arms 52 and the cylinder is also provided with two sets of stripper fingers 53 and 54, these stripper fingers being placed 180° apart and one set being placed adjacent the sheet-taking pins 51.

The sequence of operations in this run of 100 the sheets is shown in Figs. 12 to 17. In Fig. 12 a multiple sheet consisting of the sheets a , a' is shown as forwarded to the cutting cylinders and the sheet a is just being cut off by the cutting knife 47. The sheet a' is taken by the pins and carried 105 about the cylinder. After the cylinder has made a complete revolution the sheet a is advanced two sheet lengths, at which time the fingers have released the sheet a' from 110 the pins and the sheet a' is free to follow the sheet a . As the succeeding multiple sheet made up of the sheets b , b' is held by the stop 27 four single sheet lengths, as 115 shown in Fig. 12, the single sheets are forwarded to be associated with the collected product spaced apart a distance of two sheet 120 lengths, which gives time for the collecting cylinder to twice collect the product before the sheet arrives for association therewith. 125

In Fig. 5 there is shown a combination of the cutting mechanism which is shown in Figs. 3 and 4 and which may be employed under some circumstances. As here shown, there is provided a cutting cylinder 55 130

mounted on a shaft 56. This cylinder is like the cylinder 28 of Fig. 3 and is provided with cutting knives 57, 58 and a set of sheet-taking devices, as pins 59, mounted on arms 60. This cylinder is also provided with three sets of stripper fingers 61, 62 and 63, two of which are located adjacent the cutting knives, the three sets of fingers being arranged at an angle of 120°. Cooperating with this cylinder 55 is a cylinder 64 which has a circumference equal to two single sheets. This cylinder is provided with a pair of cutting woods 65, 66, spaced 180° apart and mounted on a shaft 67. This cylinder is also provided with a set of sheet-taking devices, as pins 68, mounted on an arm 69. The cylinder is also provided with two sets of stripper fingers 70, 71, placed 180° apart and close behind the cutting woods. When a triple sheet is being used the upper cylinder 55 acts as a detaining cylinder, the pins on the lower cylinder being silenced. When, however, a double sheet is being used the lower cylinder 64 acts as the detaining cylinder and the pins on the upper cylinder 55 are silenced.

Under some circumstances it may be desirable, particularly for heavy sheets, to provide a cutting mechanism in which the cutting action is effected by a shear cut, such a cut being produced by knives projecting from the cylinder and having bevel cutting faces. Where, however, such a cutting mechanism is used, because of the knife arrangement, the cylinder cannot function as a detaining cylinder. Consequently, where such a cutting mechanism is used, a separate detaining cylinder is provided. Such an arrangement is diagrammatically illustrated in Fig. 18 in which there is provided a cutting mechanism including a pair of cutting cylinders 72, 73, provided with a pair of cutting knives 74, 75. In the particular construction shown in this figure, the mechanism is operating on a double sheet, that is, a multiple sheet made up of two single sheets. To properly space these sheets a sheet length apart there is provided a detaining cylinder 76 provided with sheet-taking devices, indicated at 77, this cylinder being the circumference of a single sheet. For forwarding the sheet from the cutting cylinder to the detaining cylinder there is provided a pair of forwarding rolls 78, 79. In Fig. 19 there is shown a construction operating similar to that shown in Fig. 18. In the modification in Fig. 19 the cutting knife 80 is a reciprocating knife cooperating with the block 81 to sever the sheet. In Fig. 20 is shown a further modification which may be employed under some circumstances. In this modification there is shown a reciprocating cutting knife 82 and cooperating with a block 83 which cuts the first sheet which is fed on its way by the forward-

ing rolls 84, 85. In the modification shown in this figure instead of a cylinder for detaining the second single sheet there are provided detaining fingers 86 which hold the sheet against a suitable abutment, as the plate 87. After the first sheet has been forwarded a sheet length these fingers are operated in any suitable manner to lift and a drop roller 88 forwards the second sheet to the forwarding rolls 84, 85, the knife 82 having been lifted out of the way.

In the construction so far described the single sheets separated from a multiple sheet are associated with the collected product and the timing of the sheets is effected, in the specific mechanism illustrated, by detaining the sheets. In some instances it may be desirable to associate the sheets with an uncollected product, that is, a product coming directly from the press which is not collected and which, therefore, is forwarded to the delivery substantially continuously. Where this is to be done, the single sheets must be associated with the product substantially continuously, there being but a small space permissible between the successive sheets corresponding to the small space between successive products as they come from the press. Consequently, timing of the sheets to effect proper association with the product must be effected in a somewhat different way, and a mechanism is provided by the present invention for doing this. In most sheet feeders the paper or surface speed of the feeder is somewhat greater than the press speed, that is, the actual feeding movement of one sheet by the feeder is faster than the product speed of the press. This fact is taken advantage of by the present invention to feed the sheets in proper timed relation with an uncollected product and two ways of doing this are illustrated in Figs. 21 and 22.

Referring first to Fig. 21, there is provided a long pathway for the sheets and means for forwarding the sheets along this pathway, these means operating at different speeds. In the construction shown, there is provided a sheet-forwarding mechanism including tapes 90 which pass over pulleys 91, 92, on shafts 93, 94. These tapes are operated at the high surface speed of the sheet feeder from which the sheets are forwarded in the direction of the arrow. The sheets are double sheets, that is, each sheet consists in length of two single sheets. These sheets are forwarded by the high speed tapes against a stop 95 by which the sheet is jogged or aligned. The sheet is then forwarded to a second forwarding mechanism which operates at the press speed which, as stated, is lower than the surface speed of the feeder. These forwarding means include tapes 96 passing over pulleys 97 on the shaft 94 and pulleys 98 on shaft 99. The

usual drop rollers 100, 101, may be provided for forwarding the sheet from the tapes. From the tapes 96 the sheets pass to a cutting mechanism, indicated as a pair of cutting cylinders 102, 103, by which the multiple sheet is divided into single sheets and the sheets are forwarded through guides 104 to be associated with the products. It may be desirable to utilize this same mechanism for a collected product as previously described. The cylinder 102 is, therefore, provided with pins 105. Products are associated at a pair of rolls 106, 107, and the roll 107 may, if desirable, be a collecting cylinder. With this construction, after the mechanism starts in operation, a substantially continuous stream of sheets is fed to the rolls 106, 107, because, as the paper speed of the feeder is greater than the paper speed of the press, the sheets have a chance to catch up with each other and the tape pathways are made of such length as to permit this. It will be understood that the multiple sheets are forwarded at the high speed of the feeder until the tail of the sheet has passed the drop roll 100, at which time they are brought under the control of the tapes running at press speed.

The pathway for the sheets shown in Fig. 21 may be inconvenient in some instances because of its length. Where pressroom conditions, therefore, require a shorter pathway, a shorter mechanism and arrangement, such as shown in Fig. 22, is provided. In the construction here illustrated the multiple sheets are fed in the direction of the arrow from the feeder alternately to an upper and lower sheet-forwarding mechanism, the mechanisms being superposed and thus shortening the machine. As illustrated there are provided upper forwarding tapes 108 which pass over pulleys 109 on a shaft 110 and pulleys 111 on a shaft 112. The lower forwarding mechanism includes a set of tapes 113 which pass over pulleys 114 on the shaft 110, guide pulleys 115 and pulleys 116 on a cross shaft 117. This lower mechanism also includes a set of tapes 118, which pass over pulleys 119 on a shaft 110 and over pulleys 121, similar to the pulleys 115, and over guide pulleys 122, the tapes 118 and 113 acting as a guideway for directing the sheets to the lower sheet pathway. The sheets are alternately directed to the lower pathway by means of a switch 123 which is operated in a suitable way to effect this switching function.

These upper and lower sheet-forwarding mechanisms run at the slow speed of the press and the sheets are forwarded to them at the high speed of the feeder. As the sheets are forwarded they are brought up against upper and lower stops 124, 125, by which the sheets are jogged. From the stops the sheets pass to cutting mechanism, which

may be reciprocating cutting knives 126, 127, and from the cutting knives pass to timing rolls 128, 129, 130, 131. With this construction, an upper multiple sheet is fed to the cutter 127 and divided into two sheets 70 which are fed to the timing rolls 128, 129, and associated with two successive products at that time. In the meantime, a second sheet has been forwarded to the lower cutting knife 126, there divided into two sheets 75 and associated with the next two products, so that the sheets may be continuously associated with uncollected products.

Any suitable mechanism may be employed for driving the parts of the machine. As 80 illustrated in Figs. 1 and 2, various mechanism are driven by a power shaft 132, this shaft being driven from any source not illustrated. This shaft is suitably supported in side frames 3 of the machine and outside the frame carries a driving gear 133. Inside the frames the shaft carries a gear 134 which meshes with a gear 135 on the shaft 136 which carries rolls 44, thus driving these rolls. The gear 133 is in mesh with an intermediate 137 on a stud 138 mounted in side frames of the machine. This intermediate 85 is in mesh with and drives a pinion 139 on the end of a shaft 140 on which the rolls 43 are mounted. This shaft 140 also has a gear 141 which meshes with a gear 142 on the shaft 143 on which the roll 42 is mounted. Gear 137 is also in mesh with a gear 144 on the shaft 31 of the cylinder 29 and this gear, in turn, is in mesh with a gear 146 on the shaft 30 of the cutting cylinder 28. The gear 144 is also in mesh with an intermediate gear 146' on a stud 147 suitably mounted in the side frames of the machine and this intermediate is in mesh with a gear 148 on a 95 cross shaft 149 suitably mounted in the side frames of the machine. This gear 149 is in mesh with an intermediate 150 on a stud 151 and this gear 150 is in mesh with and drives a gear 152 on the shaft 13, before referred to, and this gear 152 is in mesh with a gear 153 on the shaft 16, before referred to. 100

It will be understood that after the cover or insert, whichever the sheet may be, has been associated with the product, the product will be delivered in any suitable manner either directly or to a folding mechanism, not shown, if the product and associated cover or insert are to be folded. 115

While the invention is shown and described in what is believed to be its best forms, it will be understood that various changes may be made in the specific structure shown and described without departing from the invention as defined in the claims 120 hereunto appended.

What I claim is:

1. The combination of means for forwarding products, means for forwarding a multiple sheet, means for separating the multiple sheet into two sheets, means for driving the sheet into the separating means, and means for driving the sheet into the separating means.

5 tiple sheet into single sheets for association with the products, and means for timing the association of the sheets so that one product may have a sheet associated therewith and one or more succeeding products may be forwarded without association with a sheet.

10 2. The combination of means for forwarding products, means for forwarding a multiple sheet, means for cutting the multiple sheet into single sheets for association with the products, and means for timing the association of the sheets so that one product may have a sheet associated therewith and 70 one or more succeeding products may be forwarded without association with a sheet.

15 3. The combination of means for collecting products, means for forwarding a multiple sheet, means for separating the multiple sheet into single sheets for association with the products, and means for timing the association of the sheets so that they may be associated with the predetermined selected products.

20 4. The combination of means for collecting products, means for forwarding a multiple sheet, means for cutting the multiple sheet into single sheets for association with the products, and means for timing the association of the sheets so that they may be associated with the predetermined selected products.

25 5. The combination of means adapted for forwarding uncollected products, products collected once or products collected twice, means for forwarding a multiple sheet, means for separating the multiple sheet into single sheets, means for forwarding said sheets directly for association with the product, and means adapted for detaining certain of the sheets before forwarding them so that the sheets will be forwarded in timed relation to the predetermined selected products.

30 45 6. The combination of means adapted for forwarding uncollected products, products collected once or products collected twice, means for forwarding a multiple sheet, means for cutting the multiple sheet into single sheets, means for forwarding said sheets directly for association with the product, and means adapted for detaining certain of the sheets before forwarding them so that the sheets will be forwarded in timed relation to the predetermined selected products.

35 55 7. The combination of means for forwarding collected or uncollected products, means for forwarding a multiple sheet, means for separating the multiple sheet into single sheets for association with the products, and means for timing the association of the sheets so that they may be associated with successive uncollected products or with predetermined selected products.

40 65 8. The combination of means for forward-

ing collected or uncollected products, means for forwarding a multiple sheet, means for cutting the multiple sheet into single sheets for association with the products, and means for timing the association of the sheets so that they may be associated with successive uncollected products or with predetermined selected products.

45 9. The combination of means for forwarding products, means for forwarding a multiple sheet of two or more sheet lengths, means for separating the multiple sheet into single sheets for association with the products, and means for timing the association of the sheets so that one product may have a sheet 80 associated therewith and one or more succeeding products may be forwarded without association with the sheet.

50 10. The combination of means for forwarding products, means for forwarding a multiple sheet of two or more sheet lengths, means for cutting the multiple sheet into single sheets for association with the products, and means for timing the association of the sheets so that one product may have a sheet 85 associated therewith and one or more succeeding products may be forwarded without association with the sheet.

55 11. The combination of means for collecting products, means for forwarding a multiple sheet, means for separating the multiple sheet into single sheets, means for forwarding the first single sheet directly for association, means for detaining the succeeding sheet a number of sheet lengths equal to the 90 number of collections of the product, and means for forwarding the next succeeding sheet directly for association.

60 12. The combination of means for collecting products, means for forwarding a multiple sheet, means for cutting the multiple sheet into single sheets, means for forwarding the first single sheet directly for association, means for detaining the succeeding sheet a number of sheet lengths equal to the 95 number of collections of the product, and means for forwarding the next succeeding sheet directly for association.

65 13. The combination of means for forwarding products, means for forwarding a multiple sheet, means for cutting the multiple sheet into single sheets, and a cylinder two or more sheet lengths around provided with sheet taking devices for detaining certain of the sheets.

70 14. The combination of means for forwarding products, means for forwarding a multiple sheet, a cutting cylinder for cutting the multiple sheet into single sheets, a co-operating abutment, and sheet taking devices on one of the parts for detaining certain of the sheets, the member having the sheet taking devices being two or more sheet lengths around.

75 15. The combination of means for for-

- warding a multiple sheet, a cutting cylinder having sheet taking devices for cutting the multiple sheet into single sheets and detaining certain of such sheets one or more sheet lengths, and means for preventing sheets not to be detained from passing around the cylinder.
16. The combination of means for forwarding a multiple sheet, a cutting cylinder for cutting the multiple sheet into single sheets, sheet taking pins on the cylinder for taking and detaining certain sheets one or

more sheet lengths, and stripper fingers for preventing other sheets from being taken by the cylinder. 15

17. The combination of means for forwarding a multiple sheet, means for cutting sheets therefrom and forwarding the cut sheets in a straight path, and means for associating the sheets with a selected product 20 or successive uncollected products.

In testimony whereof, I have hereunto set my hand.

ADOLPH M. ZUCKERMAN.
